UNITED STATES PATENT OFFICE.

ROBERT B. THOMPSON, OF COALPORT, PENNSYLVANIA.

PEN-POINT RELEASER.

1,027,674.

Specification of Letters Patent.

Patented May 28, 1912.

Application filed April 6, 1911. Serial No. 619,398.

To all whom it may concern:

Be it known that I, ROBERT B. THOMPSON, a citizen of the United States, residing at Coalport, in the county of Clearfield and 5 State of Pennsylvania, have invented certain new and useful Improvements in Pen-Point Releasers, of which the following is a specification, reference being had therein to the accompanying drawing.

10 This invention relates to pen holders and has for its object to provide an improved pen holder having a clamping device by means of which the pen may be removed from the holder without touching it with 15 the fingers.

The invention further has for its object to provide an improved pen holder having the pen clamping portion so constructed that ink will not pass from the sleeve on 20 to the handle.

This invention is illustrated in the accompanying drawings, wherein:

Figure 1 is a perspective view of the end portion of the improved pen holder with the sleeve in a position to release the pen. Fig. 2 is a view similar to Fig. 1 with the sleeve removed. Fig. 3 is a perspective view of the sleeve. Fig. 4 is a longitudinal sectional view through the pen holder with the 25 pen in place. Fig. 5 is a transverse sectional view along the line 5—5 in Fig. 4, looking in the direction of the arrows. Fig. 6 is an end view of the holder in a locked position. Fig. 7 is an end view of the pen in a position 30 to release the point.

This improved pen holder comprises a handle 1, which has a reduced end 2 upon which the core 3 is mounted. The core is formed of spring metal and is provided with 40 a longitudinally extending slot 4, which divides the core into the sections 5 and 6.

A fixed sleeve 7 is placed upon the core and has its inner end secured to the reduced end of the handle 1 by any suitable means, 45 such for instance, as by punching portions of the sleeve into the handle. The sleeve is provided with an annular rib 8 which is provided with a beveled face 9. The outer end portion of the stationary sleeve is provided with a cut-out portion 10 and with a sloping flange 11. The sleeve is placed upon the pen holder so that the cut-out portion 50 will be above the section 6 of the core and in alignment with the slot 4. This sleeve is 55 also formed from spring metal so that the outer portion of the sleeve is expanded and

thus permits the core to expand into the opening 10 when it is desired to release the pen point.

An outer movable sleeve 12 is placed upon the sleeve 7 and has its outer end of slightly smaller diameter than the inner end and provided with the opening 13, which is of the same dimensions as the opening 10. The inner end of the sleeve is provided with a 60 beveled face 14 so that the sleeve will fit tightly against the rib 8 and prevent it from passing between the movable sleeve and the fixed sleeve. When the movable sleeve is placed upon the fixed sleeve, the 65 outer end of the fixed sleeve is slightly compressed and assists in holding the movable sleeve in place. The flange 11 extends over the outer edge of the sleeve 12 and also assists in holding the sleeve 12 in place. After 70 the pen holder has been assembled the sleeve 12 is turned so that the opening 10 will be covered. The pen point is then placed in the space between the sleeve 12 and the section 6 of the core. The pen is 75 held in place by the expansions of the core. When it is desired to release the pen the sleeve 12 is turned so that the opening 13 will register with the opening 10 and the 80 expansions of the core will cause the pen to 85 spring out.

When it is desired to clean the pen holder the pen can be removed and the movable sleeve drawn off. The elasticity of the fixed sleeve is sufficient to cause the flange 11 to 85 hold the movable sleeve in place, but the fact that the flange is sloping causes the movable sleeve to easily ride off of the fixed sleeve when it is desired to remove it.

What I claim is:

1. A pen holder comprising a handle, a tubular core mounted on one end of said handle and formed with resilient longitudinal members, a sleeve secured to said handle and surrounding said core and formed with a longitudinal opening in its top extending to its outer end, and a rotatable sleeve mounted on said fixed sleeve and having an opening extending to its outer end and coinciding with the opening in the fixed sleeve, 100 the outer end of said fixed sleeve being bent over and forming a support for the outer end of the rotatable sleeve, 105

2. A pen holder comprising a handle, a tubular core mounted on one end of said handle and having a longitudinal slot in each side forming resilient members, a fixed 110

sleeve secured to one end of the handle and extending over said core and of greater width at its outer end than the latter, the inner end of said fixed sleeve being formed
5 with an annular rib, and its outer end formed with an outwardly flaring edge, said fixed sleeve having a longitudinal opening on its top extending to its outer end, and a sleeve rotatably mounted on said fixed
10 sleeve and having an opening extending to its outer end and coinciding with the opening

in the fixed sleeve, said rotatable sleeve bearing at one end against the rib on the fixed sleeve and at its other end against the flaring edge at the other end of said sleeve. 15

In testimony whereof I hereunto affix my signature in presence of two witnesses.

ROBERT B. THOMPSON.
